UNITED STATES PATENT OFFICE.

CHARLES HOLLIWELL, OF BROADHEATH, ENGLAND, ASSIGNOR TO THE MERTHALER LINOTYPE COMPANY, OF NEW YORK, N. Y.

MOLD AND CASTING MECHANISM OF LINOTYPE-MACHINES.

SPECIFICATION forming part of Letters Patent No. 687,627, dated November 26, 1901.

Application filed May 28, 1901. Serial No. 62,283. (No model.)

To all whom it may concern:

Be it known that I, CHARLES HOLLIWELL, of Broadheath, in the county of Chester, England, have invented certain new and useful 5 Improvements in Molds and Casting Mechanisms of Linotype-Machines; and I do hereby declare the following to be a full, clear, and exact description of the invention, such as will enable others skilled in the art to which 10 it appertains to make and use the same.

My invention relates to improvements in linotype-machines, more especially machines of the type represented in United States Letters Patent to Mergenthaler, No. 436,532, dated 15 September 16, 1890.

The object of the invention is to adapt the machine for casting linotypes of ordinary type height, as usual, and also for casting linotypes of less than the ordinary height to 20 be used in a so-called "fudge" or late-news attachment for printing-presses.

In linotype-machines a printing slug or linotype is formed in a slotted mold lying for the time being between a line of metal letter-matrices assembled temporarily against one side of the mold and the mouth of a metal-pot presented momentarily against the opposite side of the mold to close the same and deliver the molten metal thereto. The height of the 25 slug or linotype is determined by the depth of the mold from its front to its rear face, and exact precision in height is obtained by a knife acting across the rear face of the mold to trim the base of the contained linotype 30 flush therewith. In the operation of the machine the mold is moved against the assembled line of matrices and the mouth of the pot advanced tightly against the rear face of the mold. A normal or ordinary linotype 35

stands type-high, and ordinary stereo-plates and stereo-turtles are as thick as type are high. It has become the practice of late years to fix late-news linotypes in the stereo-plate or the stereo-turtle of a newspaper-press by 40 means of a detachable tray adapted to hold them type-high when it is fixed in the stereo-plate or the turtle. This tray is known as a "fudge-box." It is necessarily not deep enough to take type-high linotypes, because 45 50 the space for it in that direction is limited, so that fudge-linotypes—i. e., linotypes for late

news—are, as a rule, only about half the normal height.

The object of this invention is to adapt a linotype-casting mechanism to produce fudge- 55 linotypes whenever occasion demands more economically than other so-called improvements for the same purpose have succeeded in doing. To this end I provide the machine with a mold of less than the normal depth or 60 thickness and corresponding with the height of the fudge-linotype, and I combine with the metal-pot an operating mechanism whereby it may be advanced beyond its normal stopping-point to coöperate with the reduced 65 mold, and I also provide a movable knife adapted to operate in connection with the low mold. The mouth of the pot is preferably made longer than heretofore in order to enable it to reach the rear face of the reduced 70 mold-block. The means for varying the movement of the pot consist, preferably, in an adjustable roller interposed between the pot and its acting cam, this roller being either made with two peripheries of different diameters, either of which may be brought into 75 action at will, or combined with means by which its relation to the pot may be varied.

Referring to the accompanying figures, 80 which are to be taken as part of this specification and read therewith, Figure 1 is a side elevation, partly in section, showing the pot-cam acting through the larger roller, and thereby holding its nozzle in metal-tight contact with the rear face of a fudge mold-block 85 held for the time being by the mold-wheel in the casting position; Fig. 2, a plan showing the larger roller adjusted and locked to be acted on by the pot-cam; Fig. 3, a plan showing the smaller roller adjusted and locked to 90 be acted on by the pot-cam; Fig. 4, a front elevation of a mold-wheel, fudge-mold on it, and the knife for trimming the foot of the fudge-linotype cast in the said mold; Fig. 5, a plan corresponding with Fig. 4; Fig. 6, a 95 sectional detail plan illustrating the action of the foot-trimming knife; Fig. 7, a rear elevation of the metal-pot cam-lever, the compound antifriction-roller, and the locking device. Fig. 8 is a detail plan, Fig. 9 a side 100 elevation, and Fig. 10 a detail, all illustrating a modification of the roller and locking

device, while Fig. 11 is a detail plan, Fig. 12 a side elevation, Fig. 13 a side elevation, and Fig. 14 a plan, all illustrating a second modification of the roller and locking device.

1 (shown in Fig. 1) is the mold for the printing edge of the linotype; 2, the row of matrices; 3, the mold-wheel; 4, its bush; 5, the hole in it through which the respective normal mold-block projects far enough for the nozzle of the metal-pot to make metal-tight contact with it; 6, the metal-pot; 7, the frame that supports it; 8, the pivot-rod upon which the pot 6 and frame 7 are moved forward by the cam 10 and back by their own weight; 9, the cam-shaft turning in the direction indicated by the arrows; 10, the cam that pushes the pot 6 forward; 11, a lever swinging by its top end from a pin 12, passed through it, and a pair of rearwardly-projecting lugs 13 13, fast on the metal-pot 6; 14 14, a pair of cheeks fast on the pot-lever 11 and projecting to the rear to carry 15, the axle of the antifriction-roller; 16, a rearwardly-projecting pin pivoted by its front end to the pot-support 7 and passed through the bottom end of the pot-lever 11 to hold a cushioning-spring 17 between them. The mechanisms that impart the above-described linear and circular motions to the mold-wheel 3 are not included in the figures, because they are not modified by the present invention. The wheel is turned by an intermittently-acting pinion engaging in the gearing 18. All the parts above mentioned are as heretofore.

35 The mold-wheel 3 acts only as a carrier of the mold-block and may, as far as the present invention is concerned, be replaced by a block adapted to move rectilinearly from the casting to the ejecting position and back again. 40 It is therefore referred to hereinafter as the "mold-carrier." The mold for the printing edge of the linotype may be of any suitable construction, and the metal-pot may be moved rectilinearly instead of being rocked and by 45 any suitable means.

19 is the improved mold-block, and the slot 20 in it is the mold for the body of the fudge-linotype 28. The construction of this block 19, as well as the means by which it is held to the mold-carrier 3, is the same as heretofore, excepting that the width of the slot 20 is reduced and that the mold-block 19 not only does not enter the hole 5, but stands with its rear face at a little distance from the front of the said mold-carrier, thereby establishing a clear space between them to make the trimming of the foot of the said linotype 28 possible. The reduction in the width of the slot 20 is clearly shown in Figs. 1 and 4 at 34. It 50 extends from one end of the mold-block to the other and from the top of it downward as far as the dotted line in Fig. 4.

21 is the nozzle of the metal-pot 6, duly lengthened to meet the requirements of the 65 present invention. 22 indicates the usual metal ports through it, shown in Fig. 1 as registering with the slot 20.

23 24 are the two peripheries of the compound antifriction-roller already mentioned. The distance between the cheeks 14 14 is 70 greater than the sum of the widths of the two peripheries 23 24 by a distance sufficient to allow of the compound roller being moved along the axle 15 to make either periphery 23 or 24 run on the cam 10, the other periphery being then of course off it. 75

25 is a locking-piece pivoted on the lever 11 by the screw 26, and 27 is the operative end of it. When the smaller periphery 23 is running on the cam 10, the larger one 24 is 80 between the said cam and a cheek 14 and overlapping the former, as clearly shown in Fig. 3, so as to prevent the compound roller moving along the axle 15 toward the opposite cheek 14. When the larger periphery 24 is 85 running on the cam 10, the compound roller is prevented moving along the axle-pin 15 in either direction by one cheek 14 and the locking-piece end 27, duly dropped down between the larger portion 24 of the compound roller 90 and the opposite cheek 14, to which the said portion is then adjacent.

29 is the knife for trimming the foot of the fudge-linotype, and 30 is its cutting edge. In the Mergenthaler linotype-machine it is fixed 95 to the mold-wheel guide 31, because that shares the to-and-fro motion of the carrier 3 between its front and rear positions. As the knife 29 is wanted only during the time that the fudge mold-block 19 is in use, it is fixed 100 by some device, such as a wing-nut 32, working on a screw 33, fast in and projecting from the block 31 and over which the knife is passed, the crank 34 in the latter bearing against the block 31 to keep the edge 30 in 105 the proper position; but this knife may be fixed in any convenient position and to any suitable part, according to the construction and motions of the mold-carrier, provided that the cutting edge 30 is held in the proper 110 plane—*i. e.*, the plane of the trimmed foot of the fudge-linotype 28—and that the untrimmed foot is moved past the said edge 30.

When a normal linotype mold-block is in the working position on the mold-carrier 3, it fills 115 the hole 5, the rear face of that portion of it standing either flush with the rear face of the mold-carrier or a little to the rear of it. The length of the motions of the pot-nozzle 21 to the front and back again must then be correspondingly normal or short, and to provide for that the compound antifriction-roller is adjusted on the axle 15 so that its smaller periphery 23 shall run on the cam 10. When a fudge-linotype mold-block 19 substitutes the 120 normal one, the length of the motions of the pot-nozzle 21 to the front and back again must be correspondingly longer, and to provide for that the said roller is adjusted on the axle 15 so that its larger periphery shall run 125 on the cam 10.

The modification of the roller and locking device illustrated in Figs. 8 to 10 consists in the distance between the cam 10 and the pe-

riphery of the roller 35 being adjustable according to the distance which the nozzle 21 of the metal-pot 6 must be moved to the front to contact with the rear face of the mold-block.

5 This adjustability is effected by mounting each journal of the axle 15 in a block 36, capable of sliding in a horizontal slot 37 in the respective cheek 14, 38 being the locking-piece, having offsets 39 39 to overhang the respective cheeks 14 14 to prevent it being shaken out of position and small enough in diameter to be passed through the slots 37 in front of the two blocks 36. When the locking-piece is in the position described and illustrated in Fig. 9, the roller 35 is locked in the position to make the nozzle 21 contact with a fudge mold-block 19. If the said piece be taken out of the slots 37 37, the weight of the pot 6 will slide the cheeks 14 14 rearwardly over the blocks 36 36 till the front ends of the said slots and blocks are in contact and will keep them so, so that the roller 35 will then be in position to make the nozzle 21 contact with a normal mold-block.

25 The modification illustrated in Figs. 11 to 14 consists in the roller 40 being mounted eccentrically upon its axle 41, the amount of eccentricity establishing the same difference between its radii as there is between the radii 30 of the two peripheries 23 and 24 described in connection with Figs. 1 to 7. Consequently either is substituted for the other upon the cam 10 by turning the roller through half a circle. Such turning is effected from outside 35 of the cheeks 14 by an external spider 42, fast to the roller 40. Two of its legs 43 43, being those which coincide with the respective major and minor radii of the roller 40, are prolonged, each having a notch 44 to embrace a stud 45, 40 projecting from the respective cheek 14, as shown in Figs. 11 and 12. The roller 40 is fast to the axle 41 by any suitable means and the spider 42 held fast to it by screws 46 passed through the same into the suitably-enlarged journal 47. The opposite and smaller journal 48 is necessarily concentric with the larger one, 47.

In the Mergenthaler machine the mold disk or carrier is commonly provided with two 50 molds differing as to the size of their slots and located in the opposite sides of the center, so that one or the other may be brought into action by adjusting the carrier through a half-revolution. When my invention is applied, one of these molds may be of the ordinary height for casting type-high linotypes and the other of lower height for casting fudge-linotypes, as shown in Fig. 1. Inasmuch as the knife for coöperating with the 55 fudge-mold is located at the front of the disk and the ordinary knife at the rear of the disk, there will be no interference between them, and the machine will therefore be adapted for casting high or low slugs at will by simply 60 bringing one mold or the other into operative position and by properly adjusting the oper-

ating devices to advance the same to a greater or less extent, as demanded.

I believe myself to be the first to provide a machine adapted for casting high linotypes 70 with a shallow mold for casting low linotypes and adjusting devices by which the pot can be caused to operate with either mold at will. I also believe myself to be the first to combine in a linotype-machine with a shallow mold 75 a knife operating at the front of the mold-carrier to trim the base of the slug, thus admitting the use in one machine of both high and low molds and knives coöperating with the respective molds, and it will be understood 80 by the skilled mechanic that these improvements may be varied in detail and embodied in any form the equivalent of that herein shown.

I claim—

1. The combination of mold-carrier adapted to carry either a normal-linotype mold-block or a fudge-linotype mold-block; reciprocating metal-pot adapted to make metal-tight contact with the mold-block on the mold-carrier; 90 cam adapted to move the nozzle of the metal-pot up to the mold-block; compound antifriction-roller on the metal-pot and having two peripheries of different diameters corresponding respectively with the distances which the 95 nozzle of the metal-pot must be moved to make the contact above mentioned; and means for locking the said roller with either of its peripheries running on the said cam.

2. The combination of mold-carrier adapted 100 to carry either a normal-linotype mold-block or a fudge-linotype mold-block; reciprocating metal-pot adapted to make metal-tight contact with the mold-block on the mold-carrier; cam adapted to move the nozzle of the metal-pot up to the mold-block; compound anti-friction-roller on the metal-pot and having two peripheries of different diameters corresponding respectively with the distances which the nozzle of the metal-pot must be 105 moved to make the contact above mentioned and capable of adjustment upon its axle to put either periphery on the said cam; and means for locking the said roller in its adjusted position.

3. The combination of mold-carrier; mold-block thereon standing at a little distance therefrom and thereby establishing a clear space between them; knife adapted to trim the foot of the linotype by being held with its 110 edge in the proper plane; and means for moving the untrimmed foot of the linotype past the said edge.

4. The combination of mold-carrier adapted 115 to carry either a normal-linotype mold-block or a fudge-linotype mold-block; reciprocating metal-pot adapted to make metal-tight contact with the mold-block on the mold-carrier; cam adapted to move the nozzle of the metal-pot up to the mold-block; compound anti-friction-roller on the metal-pot and having two peripheries of different diameters cor- 120 125 130 135

responding respectively with the distances which the nozzle of the metal-pot must be moved to make the contact above mentioned; means for locking the said roller with either 5 of its peripheries running on the said cam; mold-block on the said mold-carrier, standing at a little distance therefrom and thereby establishing a clear space between them; knife adapted to trim the foot of the linotype 10 by being held with its edge in the proper plane; and means for moving the untrimmed foot of the linotype past the edge.

5. The combination of mold-carrier adapted to carry either a normal-linotype mold-block 15 or a fudge-linotype mold-block; reciprocating metal-pot adapted to make metal-tight contact with the mold-block on the mold-carrier; cam adapted to move the nozzle of the metal-pot up to the mold-block; compound anti-friction-roller on the metal-pot; having two peripheries of different diameters corresponding respectively with the distances which the nozzle of the metal-pot must be moved to 20 make the contact above mentioned and capable of adjustment upon its axle to put either periphery on the said cam; means for locking the said roller in its adjusted position; mold-block on the said mold-carrier, standing at a little distance therefrom and thereby establishing a clear space between them; knife 25

30

adapted to trim the foot of the linotype by being held with its edge in the proper plane; and means for moving the untrimmed foot of the linotype past the said edge.

6. In a linotype-machine, the combination 35 of a melting-pot adapted to coöperate with a high mold, a low mold, and devices for adjusting the pot to coöperate with one mold or the other as required.

7. In a linotype-machine, a mold-carrier 40 provided with two molds, one adapted for casting linotypes of standard height and the other adapted for casting linotypes of less height, in combination with the coöperating pot and means adjustable to advance the pot 45 a greater or less distance as demanded.

8. In a linotype-machine, the combination of the mold-carrying wheel or disk, the shallow mold applied to its front face and overhanging as shown, in combination with a 50 trimming-knife located in front of the disk and acting behind the mold substantially as described and shown.

In witness whereof I have hereunto set my hand in the presence of two witnesses.

CHARLES HOLLIWELL.
